(57) **CLAIM**

I claim the ornamental design for cat litter packaging, as shown and described.

DESCRIPTION

FIG. 1 is a front isometric view of an embodiment of cat litter packaging showing my new design.

FIG. 2 is a front elevation view thereof.

FIG. 3 is a rear elevation view thereof.

FIG. 4 is a left side elevation view thereof, the right side being a mirror image.

FIG. 5 is a top plan view thereof; and,

FIG. 6 is a bottom plan view thereof.

Any broken lines in the drawings show unclaimed subject matter and form no part of the claimed design.
